UNITED STATES PATENT OFFICE

RALPH C. SEYMOUR, DECEASED, LATE OF SHORT HILLS, NEW JERSEY, BY MARY F. SEYMOUR, EXECUTRIX, OF SHORT HILLS, NEW JERSEY, ASSIGNOR TO R. HOE & CO., INC., OF NEW YORK, N. Y., A CORPORATION OF NEW YORK

GRIPPER MECHANISM FOR PRINTING MACHINES

Application filed June 28, 1929. Serial No. 374,467.

This invention relates to improvements in gripper mechanism for handling sheets being fed to a printing machine. In the drawings, the improved mechanism is shown only as applied to the impression cylinder of a rotary printing machine, but it will be understood that other applications of the mechanism can be made.

A tumbler which engages a stationary pin or other member fixed to the frame of the machine, has heretofore been used to open and to close a gripper mechanism carried on an impression cylinder. A spring is usually connected to the gripper shaft and arranged to bias the grippers to either the open, or to the closed position, and the tumbler acts to make the spring effective to alternately open and close them.

In the mechanisms heretofore used, when the tumbler is turned to close the grippers the spring throws the gripper fingers down with such force that they frequently rebound and allow the sheet to slip, and the printing is thus thrown out of proper register. The mechanism herein disclosed overcomes this difficulty by providing a stop which arrests the motion of the grippers just before they engage the sheet, and means for then disengaging the stop and allowing the grippers to close on the sheet without rebounding.

The especial object of the invention is to provide a gripper operating mechanism that will act to close the grippers on a sheet quickly and without rebounding.

It is also an object of the invention to provide a gripper mechanism of generally improved construction, whereby the device will be simple, durable and inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed, it being understood that various changes in the precise embodiment of the invention herein disclosed may be made within

the scope of what is claimed without departing from the spirit of the invention.

Figure 1 of the drawings is a diagrammatic view of a portion of an impression cylinder of a printing machine showing the improved gripper operating mechanism and the preferred form of cooperating stop mechanism, one of the grippers being shown in the open position;

Figure 2 is a view similar to Figure 1, except that the parts are shown in the position in which the stop is acting to prevent the grippers from closing;

Figure 3 is a view similar to Figure 2 but showing the stop disengaged and the grippers closed on the sheet, the relative position of the parts being shown as viewed on the line A—A of Figure 4, and in the direction of arrow 3;

Figure 4 is a longitudinal view of a portion of the impression cylinder and stop mechanism as seen in the direction of arrow 4 of Figure 3;

Figure 5 is a fragmentary view showing the grippers in the same position as in Figure 2, but with a stop mechanism of modified form, the relative position of the parts being shown as viewed on the line B—B of Figure 6; and

Figure 6 is a fragmentary view similar to Figure 4, but showing the modified stop mechanism depicted in Figure 5, as viewed in the direction of the arrow 6 of Figure 5.

Referring to the drawings, and particularly to Figures 3 and 4, 11 indicates the side frame of a printing machine having a bearing housing 12 secured thereto, which contains a bearing in which the shaft 13 of an impression cylinder 14, is fitted to rotate.

A bearing block 15 is secured to the cylinder and provides a bearing for the gripper shaft 16, to which a plurality of grippers are secured, one being shown at 17. A tumbler head 18 is also secured to the gripper shaft 16, and is provided with a channel 19, the sides of which are engaged by tumbler pins secured to the side frames 11. One of these pins is shown at 21, located in position to engage the tumbler head as the cylinder is rotated and thus turn the shaft 16 to close

the grippers. A similar pin not shown, is suitably located and serves to engage one side of the channel at its opposite end in a well known manner to open the grippers when the sheet is to be passed on to the delivery.

An arm shown in outline at 22, is secured to the gripper shaft at a point inside the cylinder and is pivotally connected at 23, with the head of a rod 24. The lower end of this rod is not shown, but it will be understood that it is provided with a spring and guided as shown in North Patent 640,799 or in any suitable manner, means being thus provided for executing a thrust on the rod to hold the grippers open as in Figure 1, or to close them as shown in Figure 3.

In the preferred construction, a gear 25, is secured to the bearing housing 12, and meshes with an idler 26, rotatably supported on a stud 27, secured to the cylinder 14. The idler meshes with the gear 28 which rotates on the stud 29, also secured to the cylinder 14.

In the embodiment of the invention shown, the tumbler head 18 is formed with a stop engaging face 31, that engages with the face 32 of a traveling stop 33, adjustably secured to the gear 28 by means of the bolt 34, which passes through an elongated hole in the stop and is screwed into the gear.

The tumbler head 18 also carries a pin 35, which co-acts with a shoulder 36, formed on the bearing block 15, to limit the throw of the grippers when they are turned to the open position as shown in Figure 1.

As shown in the drawings the gears 25 and 28 are made with equal diameters and have the same number of teeth, their ratio may be varied however, as by making the gear 25 with twice the number of teeth in the gear 28.

In Figure 1, the cylinder is shown at the point in its rotation where the tumbler head engages the pin 21. Further rotation of the cylinder in the direction of the arrow turns the pivot 23 past the dead center of the rod 24, which then tends to rotate the gripper shaft 16 to cause the gripper 17 to close. However, the rotation of the traveling stop 33, is so timed that the stop face 32, is then in position to be engaged by the stop engaging face 31 of the tumbler head 18; and, as shown in Figure 2, the blow due to the thrust of the rod 24 is received on the stop face 32. This action prevents the gripper 17 from closing on the sheet 37 that is shown held in position to be taken.

Further rotation of the cylinder 14 causes the stop 33 to be moved to the position shown in Figure 3, where its face 32 is disengaged from the face 31, and the gripper shaft is thus free to turn, allowing the grippers to engage the sheet and press it against the abutment 38.

It will be understood that by checking the motion of the grippers for an instant just be-

fore they close on the sheet, and then releasing them, that they move through the remaining distance slower, and do not rebound from the abutment. The grippers are thus caused to engage the sheet and hold it securely in the proper position to insure correct register of the printing.

In the modified form of the invention shown in Figures 5 and 6, a stationary, although adjustable stop 41 is substituted for the traveling stop 33. The stop 41, is secured to a suitable lug 42 formed on the frame 11, being secured thereto by bolts 43 which pass through a slot in the stop 41 and are screwed into the lugs 42. Adjusting screws 44 provide means for setting the stop 41 so that the grippers will be allowed to close on the sheet at the proper point in the revolution of the cylinders. The traveling stop shown in Figures 1 to 4 inclusive is preferable to the form of stop shown in Figures 5 and 6, as with the first mentioned form, the stop face 32 may have a much greater area than in the Figure 5 form, and in consequence, the greater wearing surface thus provided, renders the part more durable. By doubling the rotative speed of the traveling stop as previously mentioned, the area of the stop face and its durability may be further increased.

What is claimed is:

1. In a sheet gripper mechanism for an impression cylinder, a plurality of grippers supported in the cylinder, means for moving the grippers to engage a sheet, and a rotating stop on the cylinder adapted to arrest the motion of the grippers momentarily before they engage the sheet.

2. In a sheet gripper mechanism, a plurality of grippers suitably supported, an abutment for the grippers, means for moving the grippers toward the abutment to engage a sheet, and a stop supported to rotate about an axis moving with the gripper support and adapted to arrest the motion of the grippers momentarily before they engage the sheet.

3. In a printing machine, a plurality of grippers supported by an impression cylinder, means for closing the grippers to engage a sheet, and a travelling stop rotating with the cylinder adapted to arrest the motion of the grippers momentarily before they engage the sheet.

4. In a printing machine, a plurality of grippers supported by an impression cylinder, means for moving the grippers to engage a sheet, and a rotating stop adapted to arrest the motion of the grippers momentarily before they engage the sheet.

5. In a printing machine, a plurality of grippers adapted to hold a sheet on an impression cylinder, means for closing the grippers to engage a sheet, and a rotating stop adapted to arrest the motion of the grippers momentarily before they engage the sheet.

6. In a sheet gripper mechanism, a gripper

shaft, grippers secured to the shaft, means for turning the shaft to cause the grippers to grip the sheet, and a rotating stop arranged to engage with a member connected with the gripper shaft, whereby the grippers are prevented from engaging with the sheet until the said member is disengaged from the stop.

7. In a sheet gripper mechanism, a gripper shaft, grippers secured to the shaft, means for turning the shaft to cause the grippers to grip the sheet, and a travelling stop arranged to engage with a member connected with the gripper shaft whereby the grippers are prevented from engaging with the sheet until the said member is disengaged from the stop.

8. In a printing machine, a plurality of grippers suitably supported by an impression cylinder, an abutment for the grippers, means for moving the grippers toward the abutment to engage a sheet, and a stop rotatably supported on the cylinder, adapted to arrest the motion of the grippers momentarily before they engage the sheet; said stop being arranged to move relatively to the grippers while their motion is arrested.

9. In a printing machine, a plurality of grippers rotatably supported by an impression cylinder, an abutment for the grippers, means tending to move the grippers toward the abutment to engage a sheet, a stop supported to rotate with the cylinder and adapted to arrest the motion of the grippers momentarily before they engage the sheet; said stop being arranged to move relatively to the grippers while their motion is arrested.

In witness whereof I have hereunto signed my name.

MARY F. SEYMOUR,
40 *Executrix of the Estate of Ralph C. Seymour, Deceased.*
